UNITED STATES PATENT OFFICE.

WILLIAM J. McCLELLAN, OF TAUNTON, MASSACHUSETTS, ASSIGNOR TO FREEMAN-DAUGHADAY COMPANY, OF CHARTLEY, MASSACHUSETTS, A CORPORATION OF MASSACHUSETTS.

DESIGN FOR A CUFF BUTTON.

Application filed May 28, 1924. Serial No. 9,726. Term of patent 3½ years.

To all whom it may concern:

Be it known that I, WILLIAM J. McCLELLAN, a citizen of the United States of America, residing at Taunton, in the county of Bristol and Commonwealth of Massachusetts, have invented a new, original, and ornamental Design for Cuff Buttons, of which the following is a specification, reference being had to the accompanying drawing, forming a part thereof.

In said drawing, Fig. 1 is an enlarged perspective view of the face of a cuff button showing my new design; and Fig. 2 is an elevation of the cuff button.

I claim:

The ornamental design for a cuff button substantially as shown.

Signed by me at Chartley, in the county of Bristol and Commonwealth of Massachusetts, this 27 day of May, 1925.

WILLIAM J. McCLELLAN.
